DISPENSING CONTAINER FOR LABELS AND THE LIKE

Filed April 20, 1948

FIG. 1

UNITED STATES PATENT OFFICE

2,621,787

DISPENSING CONTAINER FOR LABELS
AND THE LIKE

Warren R. Harris, Elkins Park, Pa.

Application April 20, 1948, Serial No. 22,033

3 Claims. (Cl. 206—57)

1

This invention relates to dispensing containers for labels and the like and more particularly to an improved container which is light in weight, easy to manufacture and which is effective for the dispensing of labels as required.

In certain fields of merchandising, for the purpose of marking the goods, a variety of different gummed labels is employed. If the label contains the name of the particular product, a stock of different labels must be available for labelling each of the products thus identified. The storage of assorted groups of labels has heretofore proved troublesome. In many instances, injury to the labels has occurred by soiling. Other spoilage has also occurred.

It is the principal object, therefore, of the present invention to provide a dispensing container which is particularly adapted to contain a plurality of gummed labels and the like, and in which the face of the label to be dispensed is displayed for identification and ready for dispensing.

It is a further object of the present invention to provide a dispensing container for gummed labels and the like having improved provisions for maintaining the stock of labels therein in position for successive dispensing of individual labels.

It is a further object of the present invention to provide a dispensing container for gummed labels and the like in which the labels are resiliently advanced and held for dispensing, and in which the degree of resiliency may be varied, if and as desired.

Other objects and advantageous features of the invention will be apparent from the specification and claims.

The nature and characteristic features of the invention will be more readily understood from the following description, taken in connection with the accompanying drawings forming part hereof, in which:

Figure 1 is a top plan view of the blank or sheet from which the container is made, the same being shown in the flat condition before being set up;

Fig. 2 is a perspective view of the dispensing container in accordance with the present invention;

Fig. 3 is a top plan view thereof, and

2

Fig. 4 is a sectional view taken approximately on the line 4—4 of Fig. 3.

It should, of course, be understood that the description and drawings herein are illustrative merely, and that various modifications and changes may be made in the structure disclosed without departing from the spirit of the invention.

Like numerals refer to like parts throughout the several views.

Referring now to the drawings and more particularly to Fig. 1, the sheet or blank 10 from which the dispensing container is assembled is therein illustrated, the same preferably being made from suitable paperboard or the like. The sheet or blank 10 preferably includes a side wall panel 11 having joined thereto, along a longitudinal crease line 12, another side wall panel 13, and joined thereto along another longitudinal crease line 14, parallel to the crease line 12, a side wall panel 15 similar to the side wall panel 13.

The panel 11 also has joined thereto, along a transverse crease line 16, an end wall panel 17, and joined thereto along a transverse crease line 18, parallel to the crease line 16, another end wall panel 19. Each of the side wall panels 13 and 15 has one edge thereof, which is formed as an extension of the crease line 18, with a cutaway portion to provide a tongue 20 which functions as an anchor tongue or abutment, with recesses 21 on each side of the tongue 20.

Each of the wall panels 13 and 15 is also provided, intermediate the edge having the tongue 20 and an opposite edge which is formed as an extension of the crease line 16, with a slit 210. The slit 210 is preferably of arcuate shape to provide a tongue 22, which functions as an anchor tongue or abutment, in each of the panel sections 13 and 15.

The side panel section 13 preferably has a tab 23 joined thereto, along a longitudinally extending crease line 24, the crease line 24 having a slit 25 therein. One edge 26 of the locking tab 23 is cut back from the contiguous edge line of the panel section 13 for purposes to be explained.

The wall panel section 15 preferably has a wall panel 27 joined thereto along a longitudinal crease line 28 parallel to the crease lines 12 and 14, has an edge portion 29 preferably formed as

a continuation of the edge of the contiguous panel section 15, and is provided with a cutaway portion 30 along the opposite edge thereof offset inwardly from the contiguous edge of the panel 15. The panel 21 is also preferably provided, along the edge opposite from the crease line 28, with a locking tongue 31 which is adapted for insertion in the slit 25 along the crease line 24 when the container is in set up condition.

The end panel section 17 is preferably provided, along longitudinal crease lines 32 and 33 formed as extensions of the crease lines 12 and 14, with side tabs 34 and 35, and along a transverse crease line 36, parallel to the crease line 16, with a closing tab 37.

The end panel 19 is provided with an opening 40, preferably centrally located for visual observation of the labels presented thereto and for manual withdrawal of the labels, one at a time, as hereinafter explained.

The end panel 19 preferably has joined thereto, along crease lines 41 and 42 formed as extensions of the crease lines 12 and 14, side tabs 43 and 44, and connected thereto by a crease line 45 parallel to the crease line 18, a spacer tab 46 which is adapted to be folded flat against the inner side of the end panel 19. Each of the side tabs 43 and 44 is provided along the crease lines 41 and 42 with a slotted portion to provide a tongue 47, which functions as an anchor tongue or abutment, with recesses 48 on each side thereof, preferably conforming in shape and location when assembled to the tongues 20 and recesses 21 in the panel sections 13 and 15.

Referring now more particularly to Figs. 2, 3 and 4 of the drawings, in which the dispensing container is shown in set up condition, to effect this the side tabs 34 and 35 are preferably bent at right angles to the end panel 37 along the crease lines 32 and 33. The end panel 17 is bent along the crease line 16 at right angles to the panel 11 and the side tabs 34 and 35 are connected to the interior surfaces of the side wall panels 13 and 15 by gluing or the like. The side tabs 43 and 44 are preferably also bent along the crease lines 41 and 42, the end panel 19 is bent along the crease line 18 and the side tabs 43 and 44 are secured to the interior surfaces of the panels 13 and 15 by gluing, and so that the tongues 47 thereof are in alignment with the tongues 20 of side panel sections 13 and 15. The tab 46 is preferably bent inwardly and into contact with the inner surface of the adjacent portion of the end panel section 19. The container is then ready for use.

When it is desired to use the container, a band 50 of resilient material, such as rubber and preferably endless, may be hooked over the tongues 20, and 47 on one side and engaged in the recesses 21 and 48 on that side, passed under the bottom of a stack or pile 51 of labels and hooked into engagement with the tongues 20 and 47 on the opposite side and in engagement in the recesses 21 and 48 on that side. The tab 37 may then be bent along the crease line 36 into a position normal to the end panel section 17 and the tab 23 bent along the crease line 24 to a position normal to the side panel section 13. The side panel section 27 may be bent along the crease line 28 and the tab 31 inserted in the slit 25 to hold the container in closed condition.

A slot 52 is thus provided at the end of the panel section 27 adjacent the end panel 19, by the cutaway portion 30 and the cut back edge 26,

through which labels may be individually withdrawn as desired.

When the stack of labels 51 substantially fills the container, dependent upon the length of the band 50, the tension of the band 50 is ordinarily sufficient to hold the labels in engagement with the interior of the end panel section 19 and the tab 46 carried thereby. The labels may then be separately withdrawn through the slot 52 between the edge 30 of the side panel section 27 and the end panel section 19 by sliding the same upon frictional engagement by the fingers with the outermost label 51a at the opening 40. If, as labels are successively withdrawn, the tension is not sufficient to maintain the outermost label in engagement with the interior of the end panel 19, the band 50 may be stretched and hooked over one or both of the intermediate tongues 22 thereby increasing the tension of the band 50 and 20 the force exerted on the stack 51 of labels to urge the same into successive engagement with the end panel section 19 for withdrawal.

The outermost label 51a, at the opening 40, may have the desired price indicia or weight indicia, or both, marked thereon by the user with pencil or crayon prior to the withdrawal of the label through the slot 52 if desired, the tension of the band 50 being sufficient for this purpose.

I claim:

30. 1. A blank for a dispensing container formed from a single piece of flexible sheet material and having a first rectangular side wall panel, a rectangular abutment end wall panel joined at one longitudinal edge thereof to said first side wall panel along a longitudinal crease line, said abutment end wall panel having a central opening therein and an abutment tab along another longitudinal edge thereof, gluing tabs joined to said abutment panel along transverse marginal edges 35 thereof, said gluing tabs having edge cuts providing anchor tongues therein, additional rectangular side wall panels joined to said first side wall panel along transverse crease lines and adapted for engagement by said gluing tabs, said additional side wall panels having anchor tongues 40 formed therein for alignment with said first mentioned anchor tongues, and a closure side wall panel hingedly connected to one of said additional side wall panels, said closure side wall panel having a longitudinal margin cut back to provide a slot at said other longitudinal edge of 45 said abutment wall panel.

2. A blank as defined in claim 1 in which the additional side wall panels have additional anchor tongues formed therein.

3. In a dispensing container of paperboard having opposite pairs of exterior side wall panels and exterior end wall panels and a slot in one of said side wall panels of one of said pairs for the outward passage of articles disposed in a stack in the container, the end wall panel contiguous to the slot having a central opening for manual engagement with the outermost article on the stack for removal, and means for advancing the articles to the opening including an exteriorly disposed anchor tongue in each of the side wall panels of the other of said pairs, said anchor tongues extending towards the panel which is provided with the central opening and having recesses at the root portions thereof, an elastic band engaging in said recesses and having portions extending exteriorly around and in engagement with said tongues and having the remaining portions interiorly disposed and extending in engagement with the bottom of the

stack of articles, and additional exteriorly disposed band engaging anchor tongues in each of the side wall panels of the other of said pairs for retaining said band in said recesses and adjustment of the tension of the band, said additional anchor tongues being spaced along said side wall panels from said first mentioned tongues and being oppositely disposed with respect thereto.

WARREN R. HARRIS.
